UNITED STATES PATENT OFFICE.

CHARLES W. DAVIS, OF EDGEWORTH, PENNSYLVANIA, ASSIGNOR TO STANDARD UNDERGROUND CABLE COMPANY, OF PITTSBURGH, PENNSYLVANIA, A CORPORATION OF PENNSYLVANIA.

MULTIPLE-CONDUCTOR CABLE.

1,132,452.

Specification of Letters Patent. Patented Mar. 16, 1915.

Application filed January 14, 1914. Serial No. 811,980.

To all whom it may concern:

Be it known that I, CHARLES W. DAVIS, residing at Edgeworth, in the county of Allegheny and State of Pennsylvania, a citizen of the United States, have invented or discovered certain new and useful Improvements in Multiple-Conductor Cables, of which improvements the following is a specification.

10 My invention relates to the construction of multiple-conductor cables for carrying high-tension currents and its object is to increase the efficiency of cables; more specifically, by eliminating tendencies to deterioration, 15 to render such cables serviceable for longer time and capable of carrying higher voltage.

I shall describe my invention as applied to a three-conductor cable, but it will be 20 understood that it is applicable to multiple-conductor cables generally.

Three-conductor cables are ordinarily built by surrounding the individual conductors (whether solid or stranded) each in its 25 own envelop of insulation, twisting the three together into a rope with jute or like cheap filling material occupying the central triangular space and the superficial grooves formed by and between each pair of adjacent conductors, and inclosing the whole rope so filled and rounded out with what is called a belt insulation. Over the belt insulation the lead sheath or other protecting cover is applied.

30 The filling material referred to (which ordinarily is jute) has been regarded merely as a filler, and its electric properties have heretofore received no serious attention by cable engineers.

40 In high-voltage work, I have discovered the jute fillers as ordinarily employed to be themselves a source of deterioration and as such, by their very nature, restrictive upon the wider utility of the cable; and my invention 45 resides in the employment of materials of certain character or quality which will be effective to overcome the defect which I have discovered and am now pointing out.

When the cable is made in the ordinary 50 manner and high-tension alternating currents are passing in the conductors, the material within the cable sheath surrounding the individually insulated conductors and inclosed in the belt insulation, (all of which 55 is dielectric, and, ordinarily, jute) is sub-

jected to dielectric stress. The intensity of this stress varies greatly, from the geometric center of the cable (where, theoretically, the stresses are in equilibrium) to the sheath, the points of maximum stress being near 60 the points where each pair of adjacent conductors approach one another most nearly. The nature of jute is such that, under this stress, it absorbs energy, converting the energy into heat. This effect is objectionable 65 for two reasons: first, it is a useless waste of energy and (the center of the cable being unventilated) the consequent rise in temperature may char the filler, and impart heat to the insulation surrounding the individual conductors and tend to the breaking-down of that insulation—for, with materials used for that purpose, the energy loss increases as the temperature rises.

I have discovered that if layers of conducting material be interposed between the insulation of the individual conductor and the filling material, the filling material, relieved of the stress mentioned, will cease 70 to be subject to deterioration and will cease 75 to be a heat generator, and therefore will cease to be a hindrance, as it otherwise is, to a wider use of the cable. Incidentally, it is to be observed that such a layer of conducting material if present, being a conductor 80 of heat as well as of electricity (as is true of metals) will by its presence tend to a distribution of whatever heat may be generated locally within the insulation surrounding the individual conductors. This is 85 a practical advantage which is brought out in my copending application, filed November 4, 1913, Serial No. 799,090.

My invention, therefore, primarily consists in applying to the faces of the individually insulated conductors bodies of conducting material. In applying this body of conducting material, I am careful to provide that it shall not completely envelop the individual separately insulated conductor, 100 and it shall not extend circumferentially around it to an unnecessary extent, and this for the following reasons:

First, if the individually insulated conductor be wholly surrounded in metal foil 105 or in a layer of conducting material of some other character, the belt insulation ordinarily applied around the twisted and filled rope, becomes valueless as insulation, and, therefore, the presence of the conducting 110

layer would, if it extended all the way around, necessitate the increasing of the thickness of the insulation of the individual conductors and the economy of the belt insulation would be lost.

A second reason against a conducting layer wholly surrounding each individually insulated conductor is this: Insulation, however carefully made and however carefully applied, cannot be produced with absolute uniformity: there are necessarily and unavoidably points in any insulating envelop which are weaker than other points. In the making of multiple-conductor cables, the components are laid side by side, and, it will be understood, there is some danger that in the assembling, two such weak points in the insulation of two conductors may be brought opposite one another. In such case, a breakdown of insulation is a present danger and such a condition is a flaw in cable-making. But, since considerable flaws in insulation are few and far between, the danger noted is remote, and easily guarded against by the cable-maker in testing his product before putting it on the market. But, if the components of the cable are enveloped before being bunched, each in a skin of conducting material, and then placed skin to skin, the effect is to bring all weak points of the insulation of two adjacent cables opposite one another, and so insulation otherwise entirely adequate becomes quite inadequate if enveloped in foil. I therefore apply the metal foil or other conducting layers only to so much of the surfaces of the separately insulated conductors as hold between them filling material subjected to the great and destructive strains already defined.

Referring to the accompanying drawings, which form part of this specification, Figures 1 to 5 show, each of them, in cross section, a three-conductor cable embodying my invention, the specific details being various, thus indicating that my invention in its broader aspect is not limited to details of construction. Fig. 6 is a view in perspective of a central filler constructed according to my invention in one of its alternate forms; and Fig. 7 shows in end elevation another form of my central filler.

Fig. 1 shows the three conductors 1, each covered with its own insulation 2, bunched to form a cable. The inner surfaces of the bunched insulated conductor are faced with conducting material. This facing material is indicated at *a*—*b*, *c*—*d*, *e*—*f*. As has been said it may be metal foil; it may be wire-netting; it may be paper rendered conductive by a coating of metal; or it may be any other conducting material of proper shape for the intended use. The strains against which provision is intended are at a maximum near the point of nearest approach of adjacent cables; accordingly, the metal fac-

ing will preferably extend, as shown in Fig. 1, from the center of the cable outward beyond such points of closest approach. The individual insulated conductors, when they are bunched, are given a slight twist, to form a rope; accordingly, the metal facing, if applied to the individual conductors before bunching, will be laid around the individual conductors in a long spiral, so that when the cable is completed they will occupy their intended positions. If the insulation upon the individual conductors be of wrapped-on paper, as is ordinarily the case, the strip of conducting material may be laid on and retained beneath the outermost turns of the wrapping. The central filler inclosed between the metallized surfaces of the bunched insulated conductors may be of whatever character preferred—it may be jute, for, as has been explained, the presence of the metallized surfaces prevents the objectionable results otherwise attendant upon the use of jute.

As shown in Fig. 2, the layer of metal, instead of being applied to the surfaces of the insulated conductors, may be applied to the surface of the filler. And, for reasons already given, the body of the central filler will in this case preferably be extended between each pair of adjacent conductors beyond the points of nearest approach. This central body, covered with a layer of conducting material may be formed of jute and the conducting layer may be a flexible sleeve, so that the whole may be shaped as the cable is assembled; or the central body may be formed of a material which can be molded or pressed to permanent shape. In Fig. 3 such a material is illustrated. The filler is formed of rolled paper, impregnated with an insulating compound which is fluid when hot, and is pressed to shape in a die and allowed to cool and harden. The dielectric properties of such a filler are far superior to those of jute; and, as I have explained in a co-pending application, filed on even date herewith, Serial No. 811,979, a filler so made constitutes another and distinct invention of mine. But, for the purposes of this case, it is sufficient to describe a filler made of material which may be shaped, for with such material my invention is more readily practised.

As shown in Fig. 7, the layer of conducting material, instead of being applied to and sustained by an underlying body, may be made heavy enough to sustain its proper shape, and the body within may be dispensed with, the filler then becoming merely a properly shaped tube—ordinarily of metal. And it will be understood, without specific illustration, that the filler may be a solid body of metal or other conducting material.

Referring to Fig. 3, it will be seen that the metal layer may be applied to the surfaces of the individually insulated con-

ductors, not only toward the center of the group, but also beyond the points where each pair of adjacent conductors approach one another most nearly. Here layers (of 5 metal foil or other conducting material) *k-l*, *m-n*, *o-p*, cover the opposing but divergent surfaces of the conductors; and they by their presence relieve the lateral filling material of those prejudicial strains al- 10 ready mentioned, and they also serve to assist in dissipating whatever heat may be generated within the insulation of the individual conductors. The extent of the metal layer around the individual insulated con- 15 ductors will depend on conditions of in- tended service. In no case will the layer ex- 20 tend all the way around, for, over the outer- most portion of the surface, its presence is disadvantageous. Its value is greatest in 25 the vicinity of the center, and beyond the points where the individual conductors approach one another most nearly, its value decreases; and the limiting consideration is this, that, the greater its circumferential ex- 30 tent, the more objectionable is the presence of the layer, for reasons already explained.

Fig. 4 illustrates a preferred form, in which the central filler is covered with a conducting integument while the laterals are 35 formed according to and possess the ad- vantages of my invention of the application last referred to above, Serial No. 811,979. The laterals here are preferably molded or 40 pressed, being formed of coiled paper sat- 45 urated with an insulating compound of high specific inductive capacity; and the whole 50 capable of enduring dielectric strains equally in all directions.

Fig. 5 shows both central and lateral 40 fillers covered with conducting integuments.

It will be understood from what has gone before, and without further illustration, that, just as the central filler may be made solid or tubular, and wholly of conducting 55 material, so these lateral fillers also may be made wholly of conducting material and may either be tubular or solid.

It remains only to remark that the con- 50 ducting bodies whatever their circumfer- ential extent around the individually in- 55 sulated conductors, and however they may be introduced, need not be continuous throughout the length of the cable, but, for example, may be applied in bands 7 around a previously shaped filler, with intervals be- 60 tween adjacent bands. This is illustrated in Fig. 6.

I claim as my invention:

1. In a multiple conductor high-tension 60 cable, a body of conducting material cover- 65 ing the inner face of the individual insu- 70 lated conductor and extending part way 75 around such individual conductor.

2. In a high-tension cable including three or more separately insulated conductors, an 65 incomplete integument of conducting mate- 70 rial covering the opposing faces of each of the assembled insulated conductors and ex- 75 tends outwardly beyond the point where each pair of adjacent conductors approach 80 one another most closely.

3. In a multiple-conductor high-tension cable, the combination of a plurality of in- 75 dividually insulated conductors symmetri- 80 cally assembled around a central filling body, said central filling body being cov- 85 ered with an integument of conducting ma- 90 terial, such integument incompletely sur- 95 rounding said individually insulated con- ductors.

4. In a multiple-conductor high-tension cable, a central body filling the space formed by and between the assembled insulated con- 85 ductors, said filling body being covered with 90 an integument of conducting material, and a facing of conducting material incom- 95 pletely surrounding each insulated con- 100 ductor and applied to the opposing surfaces of each pair of adjacent insulated con- ductors beyond the point of their closest 105 approach, one to the other.

5. In a multiple-conductor high-tension cable, a central body filling the space formed by and between the assembled insulated con- 95 ductors, said filling body being covered with 100 an integument of conducting material, and lateral filling bodies formed of material ca- 105 pable of enduring electrical stress equally in all directions.

6. In a multiple-conductor high-tension 100 cable, lateral filling bodies filling the spaces formed by and between the assembled insulated conductors and the sheath and cov- 105 ered with integuments of conducting ma- 110 terial.

7. In a multiple-conductor high-tension cable, a central body filling the space formed by and between the assembled insulated con- 110 ductors, said filling body being covered with an integument of conducting material 115 and strips of conducting material incom- 120 pletely surrounding each insulated con- ductor and covering the opposed faces of each pair of adjacent insulated conductors, out- side the points of closest approach.

8. In a multiple-conductor high-tension cable, a facing of conducting material upon the inner face of the individual insulated conductor, such facing being non-continu- 120 ous longitudinally of the cable.

In testimony whereof I have hereunto set my hand.

CHARLES W. DAVIS.
